SNAP-ACTION GOVERNOR

Gaston Fleischel, Paris, France; dedicated (by mesme assignments) to the free use and benefit of the public

Application May 20, 1950, Serial No. 163,240

4 Claims. (Cl. 264—17)

The present invention relates in general to governors, and in particular it relates to spring loaded centrifugal governors of the astatic type. Spring loaded governors are well known, and conventionally include rotating masses which swing out from the shaft as the rotational speed thereof increases, the outward movement being opposed by an antagonistic spring. In these devices, the masses either move gradually from one extreme position to another at a rate governed by the increase of centrifugal force, as the gradual speed increase operates against increased tensioning of the resisting spring or jump between two extreme positions as the speed exceeds or drops below predetermined values, the former device being classified as a static governor and the latter as astatic governor. This motion is finally transmitted to a mechanism which adjusts or modifies the operating conditions of the apparatus sought to be controlled in accordance with the governor position.

In a large field of applications, spring loaded governors have to be effective only within a fairly narrow range around one or several definite speeds. It is the aim of the invention to provide a governor having a control member which determines the working conditions, which shifts suddenly from one operative position to another operative position. This sudden, positive shift is the snap-action referred to herein. In this invention, this snap-action is achieved by giving to the effective driving force of the governor control member, as the motion begins, an excess of force over the opposing force of the spring, taking into consideration the variation of the strength of said spring between two or more operative positions.

The main object of the present invention is the provision of a simple spring-loaded governor of the astatic type wherein the rate of increase in centrifugal force by movement of the rotating masses away from the axis of rotation against the antagonistic spring, is in excess of the increase in spring tension, above that of the preloading of said spring, in such a manner that any motion started by the centrifugal force overcoming the strength of the preloaded spring, is accelerated all along the motion, whereby the snap-action effect is achieved.

Another main object of the present invention is the provision of a spring loaded governor providing a plurality of snap-actions resulting in shifting of a control member in stepped fashion positively and suddenly from starting position to one or more successive spaced positions of equilibrium.

Other and associated main objects of the present invention are the provision of a spring loaded governor providing a snap-action effect wherein the increased spring force is suddenly overcome wholly by the increase in centrifugal force developed by the rotating masses; or alternately wherein the increased spring force is suddenly overcome partly by the increase in centrifugal forces developed by the rotating masses and partly by levers or linkage systems disposed within the governor or interposed between the governor and the opposed spring.

Another object of the invention is the provision of a spring-opposed snap-action governor wherein the movement of masses outwardly from the axis of rotation

2

causes shifting of a control member lengthwise of the rotating shift, or in any other directions through lever or other operating connections.

Further and more specific objects of the present invention will in part be obvious and in part will be specifically pointed out in the following description of several illustrative embodiments of the invention.

In the drawings annexed hereto, and forming a part hereof,

10 Figure 1 is a vertical section through one form of device constructed according to and embodying the present invention, illustrating a single governor with two spaced equilibria and characterized by the absence of linkage;

15 Figure 1A is a graphic illustration of the theoretical operation of the devices in accordance with the present invention;

20 Figure 2 is a vertical section through another embodiment of my invention as applied to a double governor with three equilibrium positions and characterized by the absence of linkage;

25 Figure 3 is a vertical section through still another embodiment of the present invention as applied to a double governor with three equilibrium positions and characterized by the absence of linkage;

30 Figure 4 is a vertical section through a further embodiment of the present invention as applied to a single governor with three equilibrium positions and characterized by the absence of linkage;

35 Figure 5 is a vertical section through a still further embodiment of the present invention as applied to a governor providing snap action resulting partly by mass movement and partly by internally arranged variable linkage;

40 Figures 6 and 7 are views partly in section and partly in side elevation of modifications of the present invention as applied to governors providing snap action partly by mass movement and partly by externally arranged levers;

45 Figure 8 is a similar view of a governor providing three equilibrium positions partly by mass movement and partly by externally arranged levers;

50 Figure 9 is a similar view of a governor providing two equilibrium positions partly by mass movement and partly by externally arranged levers, but operating at a variable angular velocity, in a predetermined range, in accordance with the requirements of the device connected therewith; and

55 Figures 10, 11 and 12 are similar views of the same type of governor providing a three position snap action, partly by mass movement and partly by externally arranged levers, operating at two different angular velocities, each variable in a given range, according to requirements of the device associated therewith.

In connection with the present invention, it will be demonstrated how a governor can actuate a signal such as an electric signal having two operative equilibrium positions, as signal on, signal off.

Referring to Figure 1, wherein means wholly within the governor are provided to achieve the desired snap-action, a jump between two equilibrium positions, my device is indicated generally by reference numeral 10 including a rotatable shaft 12 on which is axially fixed a laterally extending shell 14 having a forwardly extending cylindrical flange 16. A plurality of lengthwise slotted spider arms 18, 18 are mounted on a collar 20 fixed to shaft 12 for rotation therewith, balls or masses 22, 22 being trapped within the slotted arms 18, 18. A circular plate 24 of such diameter as to fit within the recess of shell 14 is fixed to a sleeve 26 slidably disposed about shaft 12. As illustrated, plate 24 is flat adjacent the center thereof as at 28, and has a peripheral conical portion 30 extending from a circle having a radius equal to the distance between the center-line of shaft 12 and

point 31. The normal spacing between shell 14 and plate 24, at 28, is that of the diameter of trapped balls 22, 22. The head 32 of sleeve 26 bears against an arm 34 fixed to a sliding shaft 36, behind which is disposed a helical compression spring 38, positioned between shaft 36 and a suitable stop 40. The normal compression for the preloading of spring 38 urges shaft 36, arm 34 and sleeve 26 into the position of Figure 1 with the balls 22 pressed against shell 10.

The axial shifting of collar 26 and attached plate 24 is caused by the force of rotating balls or weights 22 pushing against the inclined surface of the cone 30 which engages the balls 22 when the resolved axial component of said force against said surface is stronger than the force of the biased or preloaded spring 38. This occurs at a given angular velocity, called hereafter the governor specific velocity; below said velocity due to spring 38 action, all parts remain in the position shown in Figure 1. When the action of balls on the engaged surface of the cone 30 overcomes the force of spring 38, the cone 30 and hub 26 begin a sliding motion to the left, as in Figure 1, thereby compressing the spring 38 and increasing the force of the spring 38 urging the cone 30 and the hub 26 to the right.

To overcome this increase of resistance of spring 38 against the axial movement of shaft 36 and sleeve 26, without any change in angular velocity, it is necessary to build up sufficient force as to result in an axial movement of shaft 36 despite the increased force of spring 38. Due to the cone shape of plate 24, the axial push remains proportional to the centrifugal force developed, which increases accordingly. This result is achieved as a result of the radial movement of balls 22, 22. The centrifugal force is proportional to the radius of the center of gravity of the balls, the mass of said balls, and the square of the angular velocity thereof. Thus, since the weight or mass of the balls is a constant factor, and it is undesirable to change the angular velocity since to do so is inconsistent with the desired snap action, the only way it is possible to secure an increase in centrifugal force is by an increase in the radial positioning of the center of gravity of the balls. Such increase is obtained by forming cone portion 30 of such angularity that the ball movement between the governor in closed position, as in Figure 1, and in open position, where balls bear against the cylindrical flange 16, is large enough to insure the needed increase. That is, the increase in the axial component of the force of the balls 22 as they move radially outwardly against the surface of the cone 30 is greater than the increase in the force of the compression spring 38 as the cone 30 moves axially toward the spring 38, thus resulting in the balls 22 and cone 30 jumping from one extreme position to another.

With the structure of Figure 1, the governor operates as follows:

As long as angular velocity remains below the specific velocity, the governor remains closed, the preloaded spring being stronger than the axial push of the centrifugal force. When the specific velocity is reached, the motion starts, the force exerted by balls 22 developing to a point beyond that of the preload of the spring. This starting motion increases both the spring resistance and the force exerted by balls 22; but as the latter increase is faster than the former, the starting motion is accelerated, and the governor jumps to its open position despite the increased spring resistance. And as the balls reach the cylinder flange 16 and are held there by the continuing velocity, the governor stays open.

Figure 1A is a diagram showing the magnitude of all acting forces. Forces are plotted vertically against governor axial travel indicated as a between two extreme locations, a^1 and a^2 . Line a^1B^1 is the preloaded force of spring 38; B^1C is the force needed to overcome frictions; thus a^1C is the push developed by the centrifugal force at the specific velocity at the starting point of mo-

tion. As the motion starts, the increase of spring tension is shown by line CD while increasing centrifugal force follows line CH. The shaded area shows the excess of centrifugal force over the spring force.

There is snap action too in the return motion from open to closed position of the governor. Assuming that the governor is open, the velocity being above the specific value, and that the velocity decreases, the magnitude of the governor axial push is to be read on the vertical line a^2 , and goes down from the upper part of said line. The compressed spring resistance corresponds now to a^2B^2 with a friction loss B^2G . The return motion begins when the axial push value falls below point G and is accelerated because the slope of axial push decrease GK is more inclined than that of spring decrease GE. Thus the acting force which in that way is delivered by the spring takes advantage over the resisting one, now the governor axial push, and snap action is obtained this way too.

Hereafter, line B^1B^2 will be referred to as spring characteristic, and lines CH or GK as governor characteristic, it being understood that there is a governor characteristic for each direction of motion if friction is taken in consideration.

It is essential, therefore, that in a governor with built in snap action, the slope of the governor characteristic depending on balls or weights having radial travel must be greater than the slope of the spring characteristic.

In Figure 2, is illustrated a two-stage snap acting device contained wholly within a double governor; this device is designed in view to insure three operative positions, the governor jumping from the first to the second equilibrium position at specific velocity and from the second to the third equilibrium position at another specific velocity. Similar parts are referred to by similar reference numerals (although the effective members as 34, 42, 44 and the like have been omitted, as will be readily understood). In this device, a small shell 14a is axially and slidably mounted on an extension 12a of shaft 12 for rotation with cone 30 (as in Figure 1). However, balls 22a, 22a, trapped within shell 14a are smaller and lighter than the masses 22, 22 in shell 14. In this case, masses 22, 22 will move outwardly first, at the first specific velocity of shaft 12, shifting plate 28 and shell 14a attached thereto by collar 29 lengthwise of shaft 12. This first step snap action will be followed by a second snap action, when the second velocity of shaft 12 is reached weights 22a, 22a thereupon shifting plate 28a still further axially of the shafts and a second time creating a state of unbalance as to overcome the increased tension of spring 38. It is to be noted that masses 22, 22a originally are equidistant from the axis of rotation; but that at speed, they are unevenly spaced. The heavier masses will shift outwardly first.

As in the previous embodiment, the balls 22 and 22a, cones 30 and 30a and spring 38 are so designed that the governor characteristics are more inclined than the spring characteristic. As balls 22 and 22a have same center radius when both elementary governors are closed, the aperture angles of cones 30 and 30a are same.

Figure 3 is a device of same kind giving same results in a different way. Balls 22 and 22b are of same diameter; thus to insure two different specific velocities, balls 22 must be spaced further from shaft 12 axis than balls 22b, when both elementary governors are closed. Two shells 14 and 14b are provided, plate 24 of shell 14 being secured to shell 14b for movement therewith axially of shaft 12 and stub 12b by collar 29b, masses 22b, 22b trapped in shell 14b are closer to the axis of rotation than are masses 22, 22 in shell 14. Thus, masses 22, 22 will, in response to speed increase the shaft 12, shift out first, creating a snap action movement of stub shaft 12b through collar 29b, shell 14b, plate 28b and collar 26b.

Here as the starting radii of balls 22 and 22b are

different, the aperture angles of cones 30 and 30b must also be different.

Figure 4 is an illustration of a single governor giving three operative or equilibrium positions with built-in snap action.

In Figure 4, a two stage three position operating device is illustrated, also wholly contained within the governor assembly, wherein shaft 40 has a shell 42 secured thereto for rotation therewith, shell 40 having an annular flange 44. Within the recess of shell 42, a collar 46 is fastened to shaft 40 having radially extending slotted arms 48, 49, within which are trapped weighted balls or masses 50, 50. A plate 52 is provided, axially slidable along shaft 40 and capped by a collar 54. Plate 52 is flat adjacent the shaft, as at 56, but there are two successive conical surfaces, one 58 of wider angle aperture than the other 60; as a result the axial component of the centrifugal force which is transmitted to the plate 52 by the balls 50 is relatively greater when the balls ride along surface 58 than when they ride along surface 60. Thus, when the first specific velocity is reached, the balls jump radially until they meet the second conical surface 60 where they are stopped by the sudden decrease in the transmitted axial component of the centrifugal force which does not exceed the force of the compressed spring 38 due to the change of the profile. This is the second operative or equilibrium position of governor. But when the other specific velocity is reached, the increase of centrifugal force enables the balls to start a new jump until they reach the external flange 44, where they are stopped in the third operative or equilibrium position.

In this case, both stages have snap or step action if the less widely opened cone 60 is designed as to give to this peculiar part of the governor a more inclined characteristic than that of the spring.

To use the three equilibrium positions of said device in a practical way, any kind of control member may be used. For instance, a rod 62 may be disposed within and through the casing 64 of said control member, bearing against compression coil spring 38. Three control positions may be provided, within casing 64, as at A, B, C. Thus, as in the position of Figure 4, with masses 50, 50 against plate portion 56, rod 62 will operate through position A. When shaft 40 reaches the first specific velocity, masses 50 travel outwardly and against plate 52 at portion 58 thereof, rod 62 is snap or step shifted to position B. Similarly, when shaft 40 reaches the second specific velocity, masses 50, 50 bearing against conical surface 60 will move plate 52 still further outwardly and rod 62 will shift to position C against the further compression of spring 38.

As pointed out above, spring 38 and governor characteristic are such that as the governor speed increases from range to range, the spring will be overcome suddenly each time, permitting the snap action change through rod 62.

The embodiments of Figures 1, 2, 3 and 4 have in common the structural similarity that an adequate travel of the masses outwardly from the axis of rotation, when a specific speed of rotation is reached, is directly responsible for the snap-action through the angled faces of the axially shiftable plates and a correct inside diameter of cylinder 16. Sometimes it is difficult to build the snap action only on the travel of the governor masses. Figure 5 shows, for instance, how a governor having hinged masses may be disposed for snap action partly by the masses travel and partly by increasing the force of the axial component of the centrifugal force by an adequate design of a leverage system transforming the centrifugal force into said axial force.

In its general construction, the governor is of one well known type. Rotatable shaft 70 has fixed thereon, for rotation therewith, a collar 72 having radially extending split arms 74, 74 within which are pivoted masses 76, 76. The masses are pivoted off-center, with longer portions 77 extending rearwardly. The shorter portions 78

have mounted at their front ends rollers 80, 80. A circular plate 82 is provided, which may be flat, as shown in Figure 5, but which, within the scope of the present invention, may be conical or curved (not shown) to add an additional effect to that of the linkage; plate 82 having a recessed nose portion 84 slidably fitting over a shaft extension 86 in line with shaft 70. A lever arm 88 is pivoted as at 90, lever 88 being swingable between a rear stop 92 and a front stop 94. A compression coil spring 96 is provided, secured at one end to arm 88 and to a support 98 at its other end, spring 98 being normally biased to urge arm 88 towards stop 92 and nose 84. Plate 82 is axially slidable on shaft extension 86, but rotates therewith due to the slot and key connection as indicated at 99.

It is obvious that the electric signal 100 will not operate when the governor is closed, as in the position of Figure 5. When the governor opens, the angular motion of lever arm 88 completes the electrical circuit putting the signal in operation. A snap or jump action is necessary to insure a good make-and-break contact in the electrical circuit.

Spring 96 will function to maintain lever arm 88, nose 84, plate 82 and masses 76, 76 in the position of Figure 5 until the specific speed of rotation of shaft 70 is attained, at which time masses 77, 77, by pivoting about the ends of arms 74, 74, begin to swing outwardly. The masses 76 are so mounted and pivoted that upon the governor reaching its specific velocity the axial thrust of the centrifugal force on the weights 76 increases at a greater rate than the opposing compression spring 96 due to both the increased centrifugal force as the weights 77 swing outwardly and the increased mechanical advantage as the movement of the roller 80 approaches a path parallel to the plate 82. Consequently upon the governor reaching its specific velocity, the plate 82 and hence the control lever arm 88 will jump from the extreme position of open contacts to the other extreme position of closed contacts.

When the contacts are open the center of gravity of the governor mass 77 is positioned as indicated at R₁, the dotted line leading to the pivot 79 representing the effective torque arm of the mass 77. As the mass center of gravity rotates about 79 to position R₂ the point of contact between plate 82 and roller 80 has a decreasing torque arm which becomes zero when the line of pivot 79 and pin 81 is perpendicular to the plane of plate 82. Up to this position the more R₁ is displaced in the direction of R₂ the more effective are the masses 77 in compressing spring 96.

The embodiment illustrated in Figure 5 is provided with a leverage system within the rotating portion of the governor in order to achieve sufficient axial thrust to overcome the initial and increased opposing force of the antagonistic spring in order to obtain the snap action between spaced equilibrium points. However, when space does not permit the use of governors of this type, the effective snap action can still be obtained in accordance with my invention by disposing between the spring and the governor a linkage of such construction so as to multiply the effect of the movement of the governor control, in order to insure the characteristics illustrated by the shaded areas in Figure 1a.

This linkage structure can be incorporated within the governor, or associated with it externally. In Figure 5, the linkage structure is incorporated within the governor. In Figures 6 to 12, the linkage is externally located, but associated with the governor.

Sometimes it may be necessary to use a governor like a ball governor in which no internal variable leverage can be used, while a lack of space may not permit the mass travel necessary for the desired snap action. In this case, a suitable mechanism may be located outside of the governor and cooperate and be associated therewith, as shown on Figures 6 to 12.

In this case, the external leverage acts all along the axial travel, providing a mechanical advantage to the axial thrust or a disadvantage to the spring action in order to permit the axial thrust caused by the centrifugal forces of the rotating masses to increase at a greater rate than the opposing antagonistic force thus effecting a snap or jump action between two equilibrium positions.

In all of the devices of Figures 6 to 12, the centrifugal force is developed within a shell as 110 secured to rotatable shaft 112. Shell 110 comprises a housing within which are trapped balls or masses 114, and a governor control member in the form of cover plate 116 secured to a pin 118 slidably disposed within an axially extending recess 120 in the body of shell 110 which is fixed onto shaft 112 for rotation therewith. Control 116 may be 10 conical, as shown, but may be curved, or flattened, as will be obvious, to add an additional effect to that of the linkage, and of the masses' radius.

As the centrifugal force increases on increase in the rotational speed of shaft 112, control member 116 is 20 shifted outwardly of shell 110. However, it should be noted that the centrifugal force of the balls 114 in the device illustrated in Figs. 6 and 7 does not, by itself, increase sufficiently beyond the specific velocity to provide the snap action achieved earlier. Hence, a mechanism must be provided to effect a snap or jump action between 25 positions of equilibrium in response to a force or thrust increasing at a rate sufficient to overcome the increasing antagonistic force of the spring. This mechanism is provided externally of the rotating portion of the governor. Figure 6 shows a two position governor whose snap action is obtained by the provision of a mechanism of the aforesaid type in combination with a governor having insufficient thrust per se.

In the embodiment illustrated in Fig. 6, a bell-crank 140 is provided, having angled arms 142, 144, the lever being pivotally fixed at 146. A tension coil spring 148, secured to the end of arm 142, urges arm 142 against plate 116, arm 142 having a roller 150 at its end in rolling contact with plate 116. The other arm 144 is trapped between two stops 152, 154, and has a contact member 156 at its free end. As the resistance of spring 148 is overcome by the movement of plate 116 under the influence of masses 114, 114, arm 144 is snapped over, about its pivot 146 for instance to complete a circuit between contact 156 and a spaced contact 158.

In the above construction, the snap action is obtained upon the governor reaching its specific velocity as a result of the increasing centrifugal derived thrust as the weights move outwardly and of the increasing mechanical advantage of the governor thrust over the antagonistic spring as the lever 142 is urged counter-clockwise. When the governor overcomes the initial force of the spring 148, the arm 142 rotates counter-clockwise about pivot 146 against spring 148. However, this movement increases the component of the governor thrust acting in opposition to the antagonistic spring 148 at a greater rate than the increased tension of the spring due to the change in the revolving angle of said thrust. This results in a jump of the shell 116, crank 140 and contact 156 from its initial equilibrium position to a second extreme position of equilibrium.

In Fig. 7, there is illustrated another embodiment of the present invention of the type illustrated in Fig. 6 in which a snap or jump action between two equilibrium extreme positions is achieved by means of a suitable variable mechanical advantage mechanism. In this alternative construction, an armed lever or crank 160 is pivoted at 162, and has arm 164 with a roller 166 at its end bearing against plate 116, and an arm 168 at the other side bearing against a compression coil spring 170 bearing against a support 180. The middle arm 182 is provided with a contact 184 acting as control member of the governor and in line with a contact 185 of an electrical circuit (not shown), branch 182 pivoting between stops 186, 188 as 70

does lever arm 144 between stops 152, 154. This construction differs from that of Fig. 6 in the leverage arrangement which provides a lever for the axial push and another for the spring. It is apparent from Fig. 7 that, due to the inclination of the push lever 164 and of the spring lever 168, the axial motion, when the governor overcomes the initial force of the spring 170, increases the effective length of the push and decreases the effective length of the spring lever, thus effecting the desired snap or step action between two points.

In many installations, spring loaded centrifugal governors with snap action are used with complementary equipment. This equipment must not interfere with or prevent the desired snap-action, and, preferably, should complement same.

In Fig. 8 there is illustrated a single governor coupled with a leverage providing three spaced stepped operative positions, that is operating with snap action at two specific velocities. This construction is valuable when the governor cannot be built directly for more than two positions. The governor is shown at its closed position; a T-shaped lever 300 with a normal extension 304 terminating in a roller 306, is freely articulated on a fixed pin 306, and receives the governor axial push. A tension spring 308 with a fixed end 310, is attached to a second lever 252 freely articulated on a fixed pin 316 and this second lever actuates the control member 212 by a link 250. Along the edge of lever 252 which confronts lever 300, there are several spaced elevated fulcrum points 312 and 314. When the governor velocity is below the lowest specific velocity, both levers take the position shown in Fig. 8, lever 252 engaging the lever 300 through the fulcrum 312 and stopped by the hub of said lever, due to spring 308 action. The location of fulcrum 312 and the characteristics of spring 308 are such that when the first specific velocity is reached, the governor axial thrust rotates both levers, and said levers rotate about their respective pivots and at the same time can be regarded as having angular motion toward each other about the movable fulcrum 312 such that the flat faces forming an acute angle with fulcrum 312 as a vertex suddenly snap together in a manner similar to the action of elements 248 and 252 which are shown open in Fig. 12 and closed in Fig. 11. At the higher specific velocity, both levers are rotated again, but this time through the fulcrum 314, and assumes the position shown in Fig. 12. The location of the fulcrums 312 and 314 determines the higher specific velocity relatively to the lower specific velocity.

As can be seen in Figs. 8, 11 and 12, the successive snap or step actions at the first specific velocity about fulcrum 312 and at the second specific velocity about fulcrum 314 is achieved as a result of both the increased centrifugal derived thrust as the weights move outwardly and of the increasing mechanical advantage of the governor thrust over the force of the antagonistic spring as the shell advances axially. In the first step the thrust transmission is through the fulcrum 312 and in the second step it is through the fulcrum 314. As above set forth, the characteristics of this system is determined by the configuration of the levers, the location of the fulcrums, the position and strength of the spring and the characteristics of the rotating portion of the governor.

Some applications require a variable specific velocity within a given range as, for example, in snap-action governors for use in automatic automotive transmissions. Fig. 9 illustrates a snap-action governor with externally located cooperating linkage as applied to an automotive transmission with two different drive ratios, requiring a distributing position for each ratio. When leaving one operative position, it is highly desirable that the control member jump cleanly and quickly to the other position. However, in such installation, the specific velocity at which the jump occurs is not constant, but is required to change with the operating requirements of the engine driving the transmission. One way to obtain this variable op-

erative velocity is to add to the spring loaded governor 110 an auxiliary control device such as a vacuum operated diaphragm which is responsive to the degree of vacuum in the engine intake manifold and is a measure of the power required by the drive of the automobile at a given time.

Referring to Fig. 9, the governor 110 is mounted on a rotatable shaft 112 of the drive transmission preferably connected to the driven shaft. Near its center, or apex, governor control member 116 is flattened, and bears against a roller 202 mounted at the end of arm 204 of the bell crank 200 which is rotatably pivoted by means of pin 206. A tension spring 208 connects the end of arm 204 to a fixed point 210, and is obliquely mounted urging the bell crank 200 in a clockwise direction. The actuation of lever 200 by governor 110 is as described with respect to Fig. 6.

Assuming that control of the transmission is effected through a control device 210, as for example, an hydraulic oil distributor, having a laterally slideable rod 212, as the valve of said distributor, rod 212 is connected by link 214, to arm 216 of the bell crank 200. As the governor control member 116 moves from one operative position to another, control rod 212 is, or should have, two spaced operating positions which may correspond to two drive transmission ratios. If the spring-loaded governor 110 were the only means to cause change from one operative position to the other, this change would always occur at the same predetermined R. P. M. and at the same specific angular velocity w . The down shift would always occur at a little below w .

The governor 110 and spring 208 are preferably so constructed that the angular velocity w corresponds to the minimum of car velocity at which the shifting is desired. To provide the upper specific velocity W , another tension spring 236 is added, with one end secured to a fixed point 238 and the other end attached to a lever 232 freely articulated on pin 206 on which lever 200 also is free to rotate. To transmit the force of spring 236 to the governor, lever 232 has a shoulder 234 which is bent to engage the edge of arm 204 whereby a clockwise force may be imparted to crank 200 in addition to that of spring 208.

The vacuum equipment 222 is used to obtain all specific velocities between w and W , in operating the control 210. A closed chamber 222 is separated into two parts by a flexible diaphragm 226, with the left part connected to the intake manifold by a pipe 224, the other part being under atmospheric pressure. The guide 228 of the diaphragm is connected by a link 230 to lever 232, in such a manner as to have the force created by the vacuum acting against the spring 236. Due to shoulder 234, the vacuum force cannot act on the governor, nor on spring 208, but only reduce the action of spring 236.

When the engine is operating at full power, throttle wide open, there is no appreciable vacuum in chamber 222, and both springs exert their full strength against lever arm 204. The shifting occurs at velocity W . When the engine is operating at less than full power, throttle only part open, there is some degree of vacuum in chamber 222. The force of the vacuum exerts a pull on rod 228, link 230 and lever arm 232, thereby removing some degree of pressure from spring 236 upon lever arm 204. Thus, the main crank 200 will jump from one to the other of its equilibrium positions at a lower angular velocity. If engine load is small enough because the throttle is lightly depressed, the vacuum in chamber 222 is sufficient to overcome spring 236 and eliminate completely the effect of said spring as any factor in the spring loading of lever 204. Under such conditions, only spring 208 will be effective and the shift will occur at the predetermined number of R. P. M. w . And all intermediate shifting velocities are possible because the vacuum force can take any intermediate value between its maximum and its minimum.

If improperly designed, the vacuum may disturb the governor snap-action. At a given engine or car velocity and at a given throttle opening, the rate of the vacuum is constant all along the control member stroke while the strength of spring 236 increases when the governor opens. This would interfere with the snap-action. To correct this situation, it is desirable to provide to the subassembly comprising the vacuum device, lever 232 and spring 236 a decreasing mechanical advantage as the motion advances to help the internal motion of said sub-assembly. This is obtained by any of the means explained before, for instance by a convenient obliquity given to both link 230 and spring 236 relatively to lever 232. Rods 230 and 260 may be controlled by the throttle or accelerator pedal rather than by engine manifold vacuum acting upon diaphragms 226, if desired.

It is obvious in Fig. 9 that the increasing effective arm lever of the vacuum force when the governor opens, and the decreasing effective arm lever of the spring encourage the snap or jump action of the system due to the variation of interposed levers as explained. Outside of vacuum chamber, lever and spring, all other parts operate as explained for Figure 6.

In cases where a transmission controlled by a governor has more than two ratios, three or more, the governor must be provided with three or more operative positions in addition to the variable speed disposition explained on Figure 9.

In Fig. 10 is illustrated a three position governor arrangement for a three ratio transmission including the variable speed dispositions by vacuum with parts similar to other figures being similarly numbered. An inverted bell crank 240 is pivoted at 242. One arm 244 has a roller 246 at its end bearing against governor plate 116. The other, arm 248 of crank 240, normally depends at substantially right angles to shaft 112 at its rest position. This construction is an equivalent of the T-shaped lever 300 of Fig. 8. Control mechanism 210 has shaft 212 projecting therefrom and connected by link 250 to an arm 252 of a bell crank 254 provided with an integral arm 258. Diaphragm rod 228 is connected to a link 260 which is pivoted to lever 268 which in turn is pivoted to the joint of crank 254. The lever 268 is provided with projecting ledge 270 bearing on arm 258. Tension coil springs 272, 274 are secured to arms 268 and 258, and to fixed pins 276, 278 respectively. As governor plate 116 is shifted outwardly on increase in rotation of shaft 112, acting on lever arm 244, lever 240 pivots about 242 and arm 248 is swung against a corner 312 of an outwardly extending shoulder 280 on arm 252 said shoulder having sharp corners or fulcrums 312 and 314. The first position of the parts is illustrated in Fig. 10. This position corresponds to a governor velocity below the lower specific velocity. The second position is illustrated in Fig. 11, with arm 248 lying flatly against shoulder 280 of arm 252, at which point control rod 212 is shifted one unit into sub-assembly 210. This position is obtained when governor velocity is between both specific velocities. As the lever arm 244 is further actuated by the governor when the upper specific velocity is reached, arm 248 shifts to the position illustrated in Fig. 12, pivoting about the corner of shoulder 280 moving control 212 still further into the sub-assembly 212, the three control positions being indicated, for instance, at J, K and L (Fig. 10).

All of the governors may be provided with restoring springs to return them to a position of low or zero speed of rotation. However, spring 308 preferably returns cone 116 as the governor force decreases. Spring 96 can likewise return masses 77 unless R_2 is permitted to move beyond the point where the line of 79—81 is perpendicular to plate 82 so as to lock. The masses 77 could then be restored by a spring acting between them or manually with a lever controlled by the operator. Normally the position R_2 is sufficient to close the contacts of circuit 75 100 and spring 96 can restore the masses 77. In Fig. 7

as the governor force drops with the contacts 184, 185 closed, spring 170 rotates arm 182 clockwise and restores governor 110. Spring 148 has the same action in Fig. 6 and also spring 208 in Fig. 9 and spring 274 in Fig. 10. The governor devices are primarily automatic control means and are self-restoring.

This structure is a combination of the multi-position device shown in Fig. 8 with the variable velocity disposition explained in Fig. 9. Thus, all complementary explanations given for such figures apply here, as apply all precautions to be taken relatively to multiple positions and vacuum levers. The result is a multiple position and variable angular velocity governor with snap-action not impaired in any way by any of the additions imposed upon by the special use of the governor.

In summary, snap-action can be built completely inside of any kind of governor by designing the travel of center of gravity of masses long enough in accordance to the spring increase; this way, the snap-action results from an increase of radius of center of gravity of masses which is faster than the increase of the force of the antagonistic spring all along the axial motion of the governor. This applies as well to single governors with two operative positions, Fig. 1, or with more than two positions, Fig. 4, or to more complicated governors like those shown in Figs. 2 and 3.

If the travel of the masses cannot be built up enough to provide the wanted snap-action, an increase of the governor axial push relatively to the centrifugal force can be produced in some kinds of governors by simple alteration of the internal leverage transforming the centrifugal force into the axial push of the governor—example, Fig. 5, relative to a hinged governor.

If both adequate masses travel and internal leverage cannot be designed as to insure completely the wanted snap-action, then an external variable leverage has to be used. Figures 6 and 7 show this solution for a single governor having two operative positions and Fig. 8 for a single governor completed by a lever device conferring to it more than two positions.

If one or several variable operating velocities are needed, and special devices added to the governor for this purpose, these devices like the multi-position mechanisms, must not bring trouble to the snap-action and have to be carefully checked. The correct mounting of a variable velocity mechanism in supplement to an external snap-action leverage is shown in Figure 9 with a single two position governor.

Of course, some precautions have to be taken with any multiple position device; Figures 10, 11 and 12 show how to assemble correctly a variable velocity mechanism and a multi-position device with a single governor provided with an external snap-action leverage.

I claim:

1. A governor mechanism of the type described comprising a rotatable member, a weight eccentrically mounted relative to the axis of rotation of said member and adapted to rotate therewith, said member being provided with a radially extending guide engaging said weight and restricting the path of movement thereof, a thrust member axially slid able relative to said rotatable member and having a portion thereof registering with said guide and sloping toward the opposing portion of said guide as said portion extends radially outwardly, a varying mechanical advantage link mechanism and biased spring means having a characteristic constant selected to provide a first rate of force increase and acting through said link mechanism urging said thrust member toward said rotatable member whereby said sloped portion bears against said weight, the relative angle of said sloped portion with respect to the axis of rotation being such that for a velocity of rotation of said weights equal to the specific governor velocity for the combination, the reactive force required to be exerted on said conical surface to maintain the weights in position increases at a rate greater than said first rate of force

increase, said angle of slope and the characteristics of said link mechanism and said spring means being such that upon said rotatable member rotating at a predetermined speed the thrust imparted to said thrust member by said weights as a result of the centrifugal force thereof is sufficient to overcome the opposing thrust of the spring means through said link mechanism causing said thrust member to recede from said rotatable member and permitting said weight to move radially outward, the rate of increase of the thrust due to the increased centrifugal force on said weights as they move outwardly and the increased mechanical advantage of said link mechanism in favor of said thrust member being greater than the rate of increase of thrust of the opposing spring means thereby resulting in said thrust member jumping in snap fashion from its initial point to a second point of equilibrium where the force opposing further axial movement of the thrust member is at least equal to the centrifugal force derived thrust, said link mechanism comprising a pivoted bell crank having one arm bearing against said thrust member and the other arm connected to said spring means whereby upon rotation of said bell crank by said thrust member the moment arm and relative tangential component of the thrust of said thrust arm increases and the moment arm and relative tangential component of said spring means decreases and wherein means are provided for varying the loading of said spring means in response to a predetermined control.

2. A governor mechanism of the type described comprising a rotatable member, a weight eccentrically mounted relative to the axis of rotation of said member and adapted to rotate therewith, said member being provided with a radially extending guide engaging said weight and restricting the path of movement thereof, a thrust member axially slid able relative to said rotatable member and having a portion thereof registering with said guide and sloping toward the opposing portion of said guide as said portion extends radially outwardly, a varying mechanical advantage link mechanism and biased spring means having a characteristic constant selected to provide a first rate of force increase and acting through said link mechanism urging said thrust member toward said rotatable member whereby said sloped portion bears against said weight, the relative angle of said sloped portion with respect to the axis of rotation being such that for a velocity of rotation of said weights equal to the specific governor velocity for the combination, the reactive force required to be exerted on said conical surface to maintain the weights in position increases at a rate greater than said first rate of force increase, said angle of slope and the characteristics of said link mechanism and said spring means being such that upon said rotatable member rotating at a predetermined speed the thrust imparted to said thrust member by said weights as a result of the centrifugal force thereof is sufficient to overcome the opposing thrust of the spring means through said link mechanism causing said thrust member to recede from said rotatable member and permitting said weight to move radially outward, the rate of increase of the thrust due to the increased centrifugal force on said weights as they move outwardly and the increased mechanical advantage of said link mechanism in favor of said thrust member being greater than the rate of increase of thrust of the opposing spring means thereby resulting in said thrust member jumping in snap fashion from its initial point to a second point of equilibrium where the force opposing further axial movement of the thrust member is at least equal to the centrifugal force derived thrust, said link mechanism comprising a pivoted bell crank having a plurality of spaced fulcrum points on one arm thereof and having the other arm connected to said spring means, and a pivoted lever bearing against said thrust member and engaging one of said fulcrum points furthest removed from the pivoted end of said bell crank when said governor mechanism is in rest position and engaging at said second point of equilibrium

another of said fulcrum points more closely spaced to the pivoted end of said bell crank the force of the thrust member being insufficient, at said predetermined speed, to overcome the force of the loaded spring means through said other fulcrum point but upon said weights being rotated at a second greater predetermined speed said thrust member jumps in snap like fashion to a third equilibrium position in a manner similar to the action from said initial position to said second equilibrium position.

3. A governor mechanism of the type described comprising a rotatable member, a weight eccentrically mounted relative to the axis of rotation of said member and adapted to rotate therewith, said member being provided with a radially extending guide engaging said weight and restricting the path of movement thereof, a thrust member axially slidable relative to said rotatable member and having a portion thereof registering with said guide and sloping toward the opposing portion of said guide as said portion extends radially outwardly, a varying mechanical advantage link mechanism and biased spring means having a characteristic constant selected to provide a first rate of force increase and acting through said link mechanism urging said thrust member toward said rotatable member whereby said sloped portion bears against said weight, the relative angle of said sloped portion with respect to the axis of rotation being such that for a velocity of rotation of said weights equal to the specific governor velocity for the combination, the reactive force required to be exerted on said conical surface to maintain the weights in position increases at a rate greater than said first rate of force increase, said angle of slope and the characteristics of said link mechanism and said spring means being such that upon said rotatable member rotating at a predetermined speed the thrust imparted to said thrust member by said weights as a result of the centrifugal force thereof is sufficient to overcome the opposing thrust of the spring means through said link mechanism causing said thrust member to recede from said rotatable member and permitting said weight to move radially outward, the rate of increase of the thrust due to the increased centrifugal force on said weights as they move outwardly and the increased mechanical advantage of said link mechanism in favor of said thrust member being greater than the rate of increase of thrust of the opposing spring means thereby resulting in said thrust member jumping in snap fashion from its initial point to a second point of equilibrium where the force opposing further axial movement of the thrust member is at least equal to the centrifugal force derived thrust, said link mechanism comprising a pivoted bell crank having a plurality of spaced fulcrum points on one arm thereof and having the other arm connected to said spring means, and a pivoted lever bearing against said thrust member and engaging one of said fulcrum points furthest removed from the pivoted end of said bell crank when said governor mechanism is in rest position and engaging at said second point of equilibrium another of said fulcrum points more closely spaced to the pivoted end of said bell crank the force of the thrust member being insufficient, at said predetermined speed, to overcome the force of the loaded spring means through said other fulcrum point but upon said weights being rotated at a second greater predetermined speed said thrust member jumps in snap like fashion to a third equilibrium position in a manner similar to the action from said initial position to said second equilibrium position, and auxiliary second spring means responsive to a control device for imparting a supplementary variable moment to said bell crank in the same direction as said first spring means thereby to correspondingly vary said first and second predetermined snap activating speeds.

4. A governor mechanism of the type described comprising a rotatable member, a weight eccentrically mounted relative to the axis of rotation of said member and adapted to rotate therewith, said member being provided with a radially extending guide engaging said weight and

restricting the path of movement thereof, a thrust member axially slidable relative to said rotatable member and having a portion thereof registering with said guide and sloping toward the opposing portion of said guide as said portion extends radially outwardly, a varying mechanical advantage link mechanism and biased spring means having a characteristic constant selected to provide a first rate of force increase and acting through said link mechanism urging said thrust member toward said rotatable member whereby said sloped portion bears against said weight, the relative angle of said sloped portion with respect to the axis of rotation being such that for a velocity of rotation of said weights equal to the specific governor velocity for the combination, the reactive force required to be exerted on said conical surface to maintain the weights in position increases at a rate greater than said first rate of force increase, said angle of slope and the characteristics of said link mechanism and said spring means being such that upon said rotatable member rotating at a predetermined speed the thrust imparted to said thrust member by said weights as a result of the centrifugal force thereof is sufficient to overcome the opposing thrust of the spring means through said link mechanism causing said thrust member to recede from said rotatable member and permitting said weight to move radially outward, the rate of increase of the thrust due to the increased centrifugal force on said weights as they move outwardly and the increased mechanical advantage of said link mechanism in favor of said thrust member being greater than the rate of increase of thrust of the opposing spring means thereby resulting in said thrust member jumping in snap fashion from its initial point to a second point of equilibrium where the force opposing further axial movement of the thrust member is at least equal to the centrifugal force derived thrust, said link mechanism comprising a pivoted bell crank having a plurality of spaced fulcrum points on one arm thereof and having the other arm connected to said spring means, and a pivoted lever bearing against said thrust member and engaging one of said fulcrum points furthest removed from the pivoted end of said bell crank when said governor mechanism is in rest position and engaging at said second point of equilibrium another of said fulcrum points more closely spaced to the pivoted end of said bell crank the force of the thrust member being insufficient, at said predetermined speed, to overcome the force of the loaded spring means through said other fulcrum point but upon said weights being rotated at a second greater predetermined speed said thrust member jumps in snap like fashion to a third equilibrium position in a manner similar to the action from said initial position to said second equilibrium position, and auxiliary second spring means responsive to the pressure in the intake manifold of an internal combustion engine for imparting a supplementary variable moment to said bell crank in the same direction as said first spring means thereby to correspondingly vary said first and second predetermined snap activating speeds.
